ATTORNEY

UNITED STATES PATENT OFFICE

FREDERICK D. REYNOLDS, OF ST. LOUIS, MISSOURI

SHOE PLATE

Application filed August 11, 1930. Serial No. 474,617.

This invention relates to new and useful improvements in shoe plates.

The objects of the invention are to provide a shoe plate having a stationary member fixed to the shoe and a central member movably mounted in said stationary member and movable therein to produce clicking noise during tap dancing or walking.

Other objects of the invention are to provide a shoe plate comprising a plurality of assembled members, including a bottom plate which is movably mounted to produce the desired audible effect during tap dancing or walking.

Further objects of the invention are to provide a shoe plate comprising a retaining member fixed to the underside of the shoe and a movable member revolvably mounted in said retaining member and having a convex portion projecting outwardly from said retaining member for engagement with the floor, thereby reducing friction and facilitating whirling movement of the dancer.

Still further objects of the invention are to provide ball bearings between the revolvable plate and the supporting plate whereby the weight of the dancer is transmitted through said ball bearings from the retaining plate to the supporting plate.

With these and other objects in view, my invention consists in certain novel features of construction and arrangement of parts, hereinafter more fully described and claimed, and illustrated in the accompanying drawing, in

which—

Figure 1 is a bottom view of a shoe having the shoe plate attached to the heel.

Figure 2 is a similar view showing the shoe plate attached to the tip of the sole.

Figure 3 is a similar view showing the shoe plate attached to the shank portion of the sole.

Figure 4 is an enlarged bottom plan view of the shoe plate.

Figure 5 is a vertical cross section taken on line 5—5 of Figure 4 and showing the plate attached in position.

Figure 6 is a top plan view of a modified form of a shoe plate employing ball bearings.

Figure 7 is a vertical section taken on line 7—7 of Figure 6 and showing the shoe plate attached in position.

Figure 8 is a vertical cross section through another modified form of my improved shoe plate.

Referring by numerals to the accompanying drawing, A indicates a shoe having a sole B, a heel C, and a shank portion D.

The shoe plate 10, which is preferably circular in shape, comprises a retaining member 11 and a movable member 12. The retaining member consists of an outer plate 14 and a supporting or inner plate 15. The retaining plate or member 14 has a straight flanged portion 16 and a downwardly presented cylindrical portion 17. The lower end of this cylindrical portion is open and terminates in a horizontally and inwardly presented annular flange 18. The edge of flange 16 terminates in an upwardly presented annular flange 19. The annular flange 18 is spaced a suitable distance below flange portion 16 and forms a central opening 20.

The inner plate 15 has a straight flanged portion 21 and a central convex portion 22. Flange portion 21 lies against flange 16 of member 14 with the edge of said portion 21 fitting snugly within the upward marginal flange 19 so that the two plates are held in proper assembled relation. The central convex portion 22 curves outwardly into the chamber formed by the cylindrical portion 17.

The movable member 12 has a cylindrical body portion 24 which extends outwardly through the flanged opening 20 of member 11. The upper edge of this body portion 24 terminates in a horizontally and outwardly disposed annular flange 25 which rests upon the flange 18 of member 11 and supports member 12 in position and also prevents removal of member 12 from said member 11.

The bottom 26 of member 12 is convex or curved outwardly and forms the supporting surface for the shoe plate. Thus member 12 is revolvable within member 11 and has a certain amount of movement in vertical plane, the extent of such movement being limited on its downward stroke by annular flange 18.

and on its upward stroke by the central convex portion 22 of plate 15.

The cylindrical body portion 24 is of sufficient depth so that when movable member 12 occupies inward position with the upper edge of flange 25 bearing against the convex portion 22 the bottom 26 of plate 12 is still disposed below the horizontal plane of annular flange 18. This vertical movement of plate 12 produces, during walking or dancing, the desired clicking noise.

The convex bottom 26 of plate 24 reduces friction so that the wearer can easily spin or whirl when supported by the shoe plate. 15 This feature is particularly desirable in connection with ballet dancing in which case the shoe plate would be located at the tip of the shoe.

The plate is attached in position by suitable nails, such as 27, and the flanged portions 16 and 21 are provided with suitable apertures adapted to coincide for receiving said nails. When the shoe plate is attached in position, the upward flange 19 of member 14 is forced into the leather so that no sharp edges or abrupt surfaces are formed on the shoe plate.

In the modified form shown in Figures 6 and 7, a ball bearing 28 is located within the cylindrical portion 29 of movable plate 30. When the plate 30 moves upwardly, said ball bearing engages the convex portion of supporting plate 31, thereby providing anti-friction supporting means between said plates and facilitating the revoluble motion between the relative parts. As the plate 30 and ball bearing 28 are spaced a suitable distance from supporting plate 31, there is sufficient play between the parts to produce the desired audible effect.

In the modified form shown in Figure 8, a movable plate 32 is supported within an intermediate flanged collar 34 which in turn is supported by retaining member 35. Thus, instead of having only one movable member, there are two movable members provided, namely, plate 32 and collar 34, both of which are adapted to engage the supporting plate 36, and produce the desired audible effect.

When in retracted or inward position, the convex face 35 of plate 32 is disposed below the lowermost portions of collar 34 and retaining member 35.

The shoe plate can be attached either to the heel of the shoe, as shown in Figure 1, or to the tip of the sole, as shown in Figure 2. In some cases, as for instance when the shoe plate is used for walking only, the shoe plate can be attached to the shank portion, as shown in Figure 3. The shoe plate is formed so that all sharp corners or abrupt surfaces are eliminated so that there is no danger of injuring the floor or stumbling

on account of striking irregularities in the floor.

The component parts of the shoe plate are so constructed that they can be formed from stamping, thus reducing the cost of manufacture to minimum and providing a strong and wear-resistance structure.

I claim:

1. A shoe attachment comprising a retaining member having a cylindrical body portion open at both ends and flanged outwardly at its upper end and inwardly at its lower end, a movable member having a convex bottom disposed below the lower end of said cylindrical body portion and having an outwardly presented flanged upper end engaging the inwardly flanged lower end of said body portion, said movable member being revoluble and movable in a vertical plane with respect to said retaining member, and a closure plate closing the upper end of said cylindrical portion and engageable by said movable member upon the upward movement of the latter.

2. A shoe attachment comprising a retaining member having a cylindrical body portion open at both ends and flanged outwardly at its upper end and inwardly at its lower end, a movable member having a convex bottom disposed below the lower end of said cylindrical body portion and having an outwardly presented flanged upper end engaging the inwardly flanged lower end of said body portion, said movable member being revoluble and movable in a vertical plane with respect to said retaining member, and a closure plate closing the upper end of said cylindrical portion and engageable by said movable member upon the upward movement of the latter, said closure plate having a convex central portion extending into said cylindrical portion and being adapted to be engaged by the upper flanged end of said movable member, thereby limiting the upward movement of said movable member and providing a striking plate therefor.

3. A shoe attachment of the class described comprising a member adapted to be attached to a shoe and having a central portion extending outwardly, a bottom plate having its upper end movably mounted in said cylindrical portion and having a convex lower end extending at all times past the lower end of said cylindrical portion, and a top plate for closing the upper end of said cylindrical portion and engageable by the upper end of said movable member when the latter is moved inwardly.

In testimony whereof I hereunto affix my signature this 23rd day of July, 1930.

FREDERICK D. REYNOLDS.
